United States Patent Office

Des. 185,047
Patented Apr. 28, 1959

185,047

CHENILLE FABRIC OR SIMILAR ARTICLE

William Stark, New York, N.Y., assignor to Heritage
Weavers, Laurinburg, N.C., a partnership

Application July 9, 1958, Serial No. 51,708

Term of patent 14 years

(Cl. D92—1)

FIG. 1

I claim:

The ornamental design for a chenille fabric or similar article, substantially as shown.
